MEASURING MACHINE:

APPLICATION FILED MAR. 2, 1908.

2 SHEETS—SHEET 2.

UNITED STATES PATENT OFFICE.

CHARLES HERBERT LANTZ, OF MANHATTAN, KANSAS.

MEASURING-MACHINE.

No. 895,276.

Specification of Letters Patent.

Patented Aug. 4, 1908.

Application filed March 2, 1908. Serial No. 418,824.

To all whom it may concern:

Be it known that I, CHARLES HERBERT LANTZ, citizen of the United States, residing at Manhattan, in the county of Riley and State of Kansas, have invented new and useful Improvements in Measuring-Machines, of which the following is a specification.

My invention pertains to machines for measuring cloth and the like; and it has for its general object to provide a simple and inexpensive machine through the medium of which laces, embroideries, ribbons, dress-trimmings and other materials ordinarily rolled on a paste-board cylinder or on a card may be unwound, accurately measured and rewound, and this expeditiously and with but a minimum amount of effort on the part of the operator when the machine is driven by hand.

Other objects and advantages of the invention will be fully understood from the following description and claims when the same are read in connection with the drawings, accompanying and forming part of this specification, in which:

Figure 1 is a side elevation of a machine constituting a practical embodiment of my invention. Fig. 2 is a plan of said machine. Fig. 3 is a view partly in section and partly in elevation taken at right angles to Fig. 1. Fig. 4 is a detail view showing the covered rolls of the machine. Fig. 5 comprises disconnected views of card-holding heads comprised in my improvements. Fig. 6 is a detail view showing a modified way of connecting the heads with their complementary standards. Fig. 7 is a view of a type of head for use in connection with a cylinder the ends of which are broken. Figs. 8, 9 and 10 are fragmentary views, hereinafter referred to in detail, illustrative of a modified construction for detachably connecting the heads to their respective shafts.

Referring by letter to the said drawings and more particularly to Figs. 1 to 4, thereof: A is the base of my novel machine from which rise opposite standards B B, a fixed standard C, a fixed standard D, and transversely adjustable standards C' and D'; the standard C' being arranged in transverse alinement with the standard C, and the standard D' being arranged in transverse alinement with the standard D, all as best shown in Fig. 2. The purpose of making the standards C' D' transversely adjustable is to adapt the machine to

receive material rolls of different lengths, and the said end is attained in the manner shown in Figs. 2 and 3—that is to say, by providing the standards C' and D' with outwardly-directed feet a and arranging the said feet in guideways b and connecting the feet and the base through the medium of bolts c which extend through slots d in the bottom walls e of the guideways and are provided below said bottom walls with heads f and which are also carried upward through the feet a and are provided above the same with wing-nuts g. By virtue of this construction it will be manifest that the standards C' and D' may be adjusted toward and from the fixed standards C and D, respectively; also, that the standards C' and D' may be fixed to the base at different points in said adjustment. The machine is shown in Fig. 2 as adapted to receive the widest piece of material, and from this it follows that it is unnecessary to make either of the standards B adjustable toward and from the other.

Journaled in the standards B are felt-covered or other suitably covered rollers E and F. The roller F is arranged above the roller E, preferably in the manner shown in Fig. 4, this being advantageous since my invention contemplates carrying the material to be measured around the rollers E and F after the manner shown in Figs. 1 and 2, and also contemplates taking motion from the material-driven roller F to actuate a register G which may be and preferably is of a type well known in this art, though it may be of any other approved type without involving departure from the scope of my invention as defined in the claims appended.

Spindles H and I are arranged in the standards C' and D', respectively, and as the said spindles and their appurtenances are similar in construction a detailed description of the spindle I and its appurtenances as shown in Fig. 3 will suffice to impart a definite understanding of both spindles and the appurtenances thereof. The spindle I, Figs. 2 and 3, extends loosely through its standard D' but is not adapted to turn therein. Said spindle is connected at its outer end with an upright bar J and is arranged to move in the direction of its length with said bar. The spindle I and bar J are yieldingly held in the positions illustrated, relative to the standard D', by tractile springs K which are connected at their outer ends to the bar and have their 112

inner ends suitably fastened at *m* in sockets *n* provided in the standard, and hence it will be apparent that the springs tend to move the bar *J*, the spindle *I* and the head *L* on the latter inward; also that said springs permit of outward movement of the bar, the spindle and the head—this latter to permit of rolls of different lengths being placed and properly held between the head *L* and the opposite head *M*, presently described. The head *L* is loosely mounted on the spindle *I* and is of a type to engage and hold a paste-board cylinder—*i.e.*, is provided with prongs *p*. On the spindle *H* is a head (not shown) similar in construction to the head *L*, and on a spindle *P*, fixed in the standard *C* is a head *N*, Fig. 1, which is also similar in construction to the head *L*. The head *M* is similar in construction to the head *L* with the exception that the former has a threaded socket *r* to receive a shaft *R* Figs. 1 and 3 upon which it is fixed. Said shaft *R* is journaled in the standard *D* and is connected through the driving connection illustrated or any other suitable driving connection with a driver *S* which may be arranged to be rotated by hand power or from a suitable motor, in the discretion of the manufacturer of the machine.

By virtue of the construction described it will be manifest that when a paste-board cylinder bearing material to be measured is interposed between the head *N* on spindle *P* and the similar head on the spindle *H*, and a paste-board cylinder is mounted between the heads *L* and *M*, the said cylinders will be securely held without liability of casual displacement; and it will also be manifest that when the material is passed between the rollers *E* and *F* and is fastened to the cylinder between the heads *L* and *M*, and the said head *M* is rotated through the connection described, the material will be taken up on the cylinder between heads *L* and *M*, and incidental to its passage around the roller *F* will be accurately measured.

It will be readily gathered from the foregoing that the paste-board cylinders may be quickly and easily mounted between the pronged heads described, and that by the operation of my novel machine the unwinding, measuring and rewinding of the material can be accomplished much more quickly than when done by hand without the aid of machinery.

In some cases the paste-board cylinders hereinbefore referred to are broken at the ends, and when it is necessary to mount these damaged cylinders in the machine conical heads like the head *M*³ shown in Fig. 7 are substituted for the pronged heads described. Again when the material to be measured is of such nature that it must be wound off of a paste-board card and rewound on a similar card, a head *M*⁴, Fig. 5, 65 having a kerf or groove *M*⁵ is employed in

lieu of the pronged head *M* and heads like the head *N*⁶ of Fig. 5, in which is a kerf *N*⁷, are substituted for the other pronged heads.

When deemed expedient, instead of securing a head on the shaft *R* in the manner shown at the left of Fig. 3, a head may be detachably fixed on the driven shaft in the manner shown in Figs. 8, 9 and 10. In these figures the shaft is indicated by *R*⁸, and the heads by *M*⁹, and it will be seen that each head is fastened to its shaft by a pin or key *T* which is passed diametrically through the shaft and against a spring *U* socketed at *V* in the head. At its outer end the key is preferably kerfed as shown and adjacent to said end the key is provided with a radial projection *W*. This latter, incidental to the introduction of the key, is passed through an opening *X* extending radially from the outer end of the key bore, and then is turned in a recess *Y* to a position of alignment with the opening *X*. In this way it will be manifest that there is no liability of the key being casually displaced; and it will also be manifest that when it is desired to remove the key it is simply necessary to turn the key until the projection *W* is in alignment with the opening *X*, whereupon the spring will force the key outward, and then said key and the head *M*⁹ may be removed in the order named.

In lieu of using the spindles *H* and *I*, spindles like the spindle *I*¹⁰ of Fig. 6 may be employed, in which case heads will be keyed on the spindles after the manner of the head *L*¹¹ in said figure. It will also be noted by reference to Fig. 6 that the spindle *I*¹⁰ bears at its outer end against a spindle *I*¹² and that this latter is connected to a bar *J* similar to those before described between which bar and the adjacent standard springs *K* are arranged.

It will be gathered from the foregoing that while my novel machine is especially adapted for invoicing materials of the kind described, it may also be used to advantage in measuring such materials precedent to sale thereof. In this latter case it is simply necessary to place a cylinder or card between the unwinding heads put the material between the rollers *E* and *F* and wind off the number of yards desired.

The construction herein illustrated and described constitutes the best practical embodiment of my invention of which I am cognizant, but it is obvious that in the future practice of the invention such changes may be made in the form, construction and relative arrangement of parts as fairly fall within the scope of my invention as defined in the claims appended.

Having described my invention, what I claim and desire to secure by Letters-Patent, is:

1. In a machine for the purpose described, the combination of a base having a guide-

- way, a standard fixed to and rising from the base, a standard movable toward and from the first named standard and having a foot disposed in said guideway, means adjustably fixing said foot with respect to said base, opposite heads equipped with means for holding a material-bearing device; one of said heads being connected with one of the standards, a spindle bearing the other head and movable endwise through the other standard and having a T-bar on its outer portion, and coiled springs extending between and connecting the said T-bar and the standard in which the spindle is movable endwise.
15. 2. In a machine for the purpose described, the combination of a base having parallel guideways, two pairs of standards rising therefrom; one standard of each pair being provided with a foot disposed in one of said guideways, whereby the standard is adjustable toward and from the other standard of the pair, means for adjustably fixing the feet of the adjustable standards to the base, pairs of opposite heads carried by the standards;
- the heads of each pair being equipped with means for holding a material-bearing device and one head of each pair being loosely mounted on an endwise movable spindle and movable toward and from the other head thereof, the said spindles movable endwise through the adjustable standards and having T-bars fixed on their outer portions, coiled springs extending between and connecting the said T-bars and the adjustable standards, means for rotating a head of one pair, a register located between the pairs of heads, and means arranged to derive motion from material incidental to the passage of the material from the device in one pair of heads to the device in the other pair of heads and to actuate the register.
